CLAIM

The ornamental design for a mixer impeller, as shown and described.

DESCRIPTION

FIG. 1 is a perspective view of a first embodiment of the mixer impeller;

FIG. 2 is a back elevation view thereof;

FIG. 3 is a left side elevation view thereof;

FIG. 4 is a top plan view thereof;

FIG. 5 is a right side elevation view thereof;

FIG. 6 is a bottom plan view thereof;

FIG. 7 is a front elevation view thereof.

FIG. 8 is a perspective view of a second embodiment of the mixer impeller;

FIG. 9 is a back elevation view thereof;

FIG. 10 is a left side elevation view thereof;

FIG. 11 is a top plan view thereof;

FIG. 12 is a right side elevation view thereof;

FIG. 13 is a bottom plan view thereof; and,

FIG. 14 is a front elevation view thereof.
